UNITED STATES PATENT OFFICE.

WINTHROP D. ALLEN, OF WASHINGTON, DISTRICT OF COLUMBIA.

DESIGN FOR A MOTOR-VEHICLE BODY.

41,949.

Specification for Design.

Patented Nov. 28, 1911.

Application filed August 24, 1911. Serial No. 645,844. Term of patent 3½ years.

To all whom it may concern:

Be it known that I, WINTHROP D. ALLEN, a citizen of the United States, residing at Washington, District of Columbia, have invented a new and original and ornamental Design for Motor-Vehicle Bodies, of which the following is a specification, reference being had to the accompanying drawings, forming a part hereof.

In the drawings Figure 1 is a side eleva-

tion; Fig. 2 is a front view, and Fig. 3 is a rear view.

I claim:

The ornamental design for a motor vehicle body, as shown.

WINTHROP D. ALLEN.

Witnesses:

JAMES M. SPEAR,
BENTON M. STAHL.
